LOOM MECHANISM

Application filed December 20, 1928. Serial No. 327,367.

This invention relates to the weaving art, and is more particularly concerned with batten and batten operating mechanism for power looms.

5 One feature of the present invention is the provision of a reed-like batten with mechanism for moving said batten toward and from the fell, beating up the filling as it is inserted and coincidentally effecting a combing of the 10 warp shed. This to and fro movement is timed, preferably, to bring the batten to the fell substantially coincidently with the reversal of the heddles and of the threads of the warp shed so that on the return movement of the batten, the new shed will be 15 combed thereby and "mats" taken out.

From another aspect, another feature of the invention is the provision of a reed-like batten automatically reciprocated toward and 20 from the fell in timed relation to and during the period the shuttle remains in the shuttle box. Interference is prevented by automatically controlling and restricting the beating up and incidental combing operations to the 25 periods that the shuttle remains in its box so that "break-outs" are impossible.

A further and related feature is the provision of a reed-like batten automatically 30 movable toward and from the fell upon the entry of the shuttle in its box and during its retention in the box to press the filling thread into the fell of the cloth with the return movement of the batten effecting a 35 combing of the warp shed.

40 A further feature of the invention is the provision of a shuttle race plate having its race way portion between the shuttle boxes separate therefrom, a frame mounting a reed-like batten on which frame said race plate section is also mounted, and mechanism for 45 automatically moving said frame with its batten and race plate from a position of alignment of race plate and shuttle boxes toward the fell and reversely to aligned position in timed relation to and during the period of 50 retention of the shuttle in its box.

Another feature of the invention consists of mechanism for moving the batten previously described toward and from the fell 55 including a mount for said batten, a power

driven dual control cam, an operating member cooperating with and positively moved thereby in opposite directions, and means connecting said operating member and mount for movement in unison when and while a 55 shuttle is in its box. The dual cam control ensuring positive forward movement and return of the batten and race plate is a particular advantageous structural provision, since the movement of these parts is positively controlled by the cams and the cam shaft being coupled to the power drive of the 60 loom, the cams can be figured to synchronize with the heddle movement to permit the 65 combing of the warp sheds by the batten as previously described and also synchronized with the operation mechanism for the picker sticks throwing the shuttle to time the forward and return movement of batten and race plate to the period of inactivity of the 70 picker sticks and therefore to the time the 75 shuttle remaining in the shuttle boxes.

With the above noted and other objects in view, the invention consists in the novel features of construction, and combinations and 75 arrangements of parts as will be hereinafter more fully set forth and pointed out in the claims.

The structural features of the invention and its operation will be more clearly understood from the following detailed specification which is to be read in conjunction with the accompanying drawings forming part thereof, and in which:

Figure 1 is a top plan view of the mechanisms of the present invention mounted in a loom frame, the associated mechanism of the loom being omitted.

Figure 2 is a transverse vertical section on an enlarged scale through the loom frame on the line 2-2 of Figure 1.

Figure 3 is a vertical section through the lay beam and oscillating frame or mount carrying the reed-like batten and race plate, the section being taken on line 3-3 of Figure 2, 95 a forward position of the mount with its associated parts being shown in dotted lines.

Figure 4 is a fragmentary view in side elevation of the mechanism of Figure 2, showing the dual cam control mechanism and its 100

operating connections to the rock shaft mounting the batten carrying frame, the cams being shown in the position occupied with the shuttle out of the shuttle boxes and the race plate in alinement therewith.

5 Figure 5 is a detail of part of the cam mechanism with the dual cams in the position occupied with the shuttle in a shuttle box and the frame moved forwardly with the batten to press the filler into the fell of the cloth.

10 Figure 6 is a perspective detail of the latching end of the cam operated pitman bar which cooperates with the latch of the rock shaft crank arm and detent control of a shuttle box.

15 Figure 7 is a perspective detail of the cross bar latch carried by the upper end of the crank arm of the frame oscillating rock shaft.

20 Since the invention is concerned with special features of power looms of standard constructions, only such parts of a standard loom have been shown as are necessary to associate the mechanism of the present invention therewith.

25 In the drawings, the loom frame is of conventional form, vertical channels 2 rising at opposite sides from the side bars 1 and supporting the usual heddles, conventionally shown at 3 and their harness as well as other parts of the loom mechanism. The breast beam 4 is indicated conventionally at the end of the frame.

30 The straight stationary beam 5 extending across and supported on the frame forward of the heddles 3 is fixedly mounted on the frame and supports on the top faces of its ends at the opposite outer sides of the frame, the shuttle boxes 6 in opposed relation and fixed in alinement by the straight nature of 35 the cross beam. The shuttle 7 is thrown through the usual picker sticks 8 and their operating mechanism (not shown) which is of standard construction and need not be herein described and shown in detail. Between the side bars 1 of the frame, the top 40 face of the cross beam 5 is cut down as indicated at 9 (Figures 2 and 3) to lie in a plane below that of the base of the shuttle boxes to permit a movable race plate, hereinafter 45 described, to overlie its top face and be positioned in alinement with the bases of the shuttle boxes for the filling inserting operation. Below and forwardly of the cross beam, a rock 50 shaft 10 traverses the frame and is mounted 55 in bearings 11 applied to the upper faces of the side bars 1 of the frame with one end projecting outwardly beyond these side bars and mounting a crank arm 12 cooperating 60 with an actuating mechanism which will later be described.

65 A frame mounting and supporting a reed-like batten and a race plate section is carried by the rock shaft 10 and reciprocated there-through from a position with the race plate

aligned with the shuttle boxes forwardly toward the fell of the cloth and thence returned to initial position, this operation occurring between successive filling inserting movements of the shuttle.

70 This frame is composed of end members which in their inactive position overlie the top of the cutdown upper face of the beam 5 inwardly of and adjacent to the shuttle boxes and are cross connected at their rear ends by the frame of a reed-like batten and at their front ends by the intermediate section of the race plate resting upon and being fixed to the lower portion of these ends to align with the shuttle race formed by the bottom of the shuttle boxes.

75 These side frame members comprise angle bars whose upper horizontal arms 13 extend rearwardly over the cutdown face of the beam 5 in the inoperative position of the frame and at their rear ends are provided with short upward extensions 14 (Figures 2 and 3) to which are riveted or otherwise rigidly secured the lower ends of risers 15 extending upwardly to points beyond the 80 warp shed and which may conveniently constitute the down-turned ends of one side of the split ends of an angle bar 16 within which is housed the upper head of a reed-like batten 17, affixed to the upper ends of the risers 15, the lower head or bar of the reed batten being affixed between the lower horizontal bars 13 at their ends as seen in Figure 3. Stop blocks 18 extend rearwardly and upwardly from the upper face of the recessed or cut-down portion of the cross beam for engagement by the rear ends of the horizontal frame bar portions 13 as shown in Figure 3, to stop and position the frame with its race plate in alinement with the floors of the shuttle boxes. 85 Angular brace bars 19 forming the bent and down-turned other sides of the split ends of the angle bar 16 connect and brace the angle bar 16 to the forward ends of the horizontal bars. 90

95 The intermediate and movable section of the race plate 20 between the shuttle boxes and overlying the recessed or cut-down face of the cross beam is mounted upon the horizontal end bars 13 of the frame with its top 100 face extending in the plane of the bases or floors of the shuttle boxes by any suitable attaching means such, for example, as the end flanges 21 shown in Figure 3. This race plate extends forwardly from the batten 17 105 to a point adjacent to the forward end of the cross beam.

110 The frame as thus constituted and mounting for movement therewith the batten and intermediate section of the race plate, is supported from the rock shaft 10 for movement thereby through the downwardly extending arms 23 of the base members of the frame ends which arms 26 are bolted, riveted, 115 or otherwise fixedly attached to the upper 120

ends of the rock arms 27 mounted upon the rock shaft 10 at the inner sides of the side frame bars 1 as shown in Figures 1 and 2.

In the inactive position of this frame shown in full lines in Figure 3, which position is positively controlled through a certain cam operated mechanism hereinafter described, the intermediate section 20 of the race plate is aligned with the end sections 22 of the race plate extending inwardly from the mouths of the shuttle boxes and forming a continuation of their bases as shown in Figure 2.

Mechanism, power driven in timed relation to the operating mechanism for the heddle reversing and shuttle operating mechanism is employed to effect oscillation or reciprocation of the crank arm 12 attached to the outer end of the rock shaft 10, this mechanism including a coupling element for connecting the crank arm 12 therewith for actuation, which coupling mechanism is controlled by the shuttle through its entry in a shuttle box.

A power driven shaft 39 mounted in the frame rearwardly of the heddles 3 and toward the warp roll and which may constitute the main drive shaft of the machine or be intergeared therewith, extends outwardly from a side member 1 of the frame and has mounted upon its outer end a pair of complementary cams 40, 41 in abutting axially spaced relation on the shaft. A reciprocating actuating member in the form of a pitman bar, generally designated at 42, has its rear end formed as a flat vertical plate 43 longitudinally slotted and riding over the shaft 39, this plate having on the opposite side faces thereof, rigid cam abutments 44, 45 engaging the edge of the respective cams 40 and 41 and harnessing the pitman bar thereto. The rear end of the pitman bar has an extension 46 guided in a bracket 47 attached to the side face of the side frame member 1 (Figure 4). The bar, forwardly of the abutment 44 extends as a flat plate 48 guided for rectilinear reciprocating movement through a bracket 49 outstanding from the channeled riser bar 2 of the frame, this plate 48, from a point underlying the beam 5 forwardly to the crank arm 12 of the rock shaft, being continued as a boxing 50 open at its top and bottom faces and reduced in height at a point intermediate its ends to provide latching shoulders 51 which with the abutment formed by the inner face of the front end wall 52 cooperate with the upper end of the crank arms 12 and with a latch mounted thereon to couple the pitman bar 42 to the crank arm for reciprocation as and when permitted by certain shuttle controlled mechanism.

Referring particularly to Figures 2, 4 and 5-7, it will be seen that the upper end of the crank 12 is reduced in width as it enters beneath the boxing 50 (see Figure 4) and is formed with bifurcated ears 53 which project

above the upper edge of the boxing and with a forwardly projecting lug 54 extending forwardly over and above the front end of the boxing. The ears 53 constitute a bracket between which is mounted the depending pivot lug 55 of the latching member shown in Figure 7 and comprising a longitudinally extending bar 56 from the under face of which the pivot lug depends at a point intermediate its ends. Rearwardly of the lug, the bar 56 is provided with a cross latching bar 57 extending from opposite edges thereof and depending therefrom, the cross bar being spaced from the hinged lug a sufficient distance to position its lower edge when dropped adjacent to and against the shoulder abutments 51 of the box 50 at the end of the pitman bar with the forward edges of the ears 53 engaging the abutment surface 52 provided by the inner face of the forward end of said box to latch the upper end of the crank arm 12 to the box 50 constituting the forward end of the pitman bar. A coil spring 56^b interposed between the lug 54 and the forward end of the longitudinal bar 56 of the latch normally tends to move the cross latching bar 57 thereof downwardly into engaging relation with the abutment shoulders 51. This cross bar 57 is of sufficient depth relatively to the depth of the shouldered portions 51 so that when it is moved downwardly to engage the upper edge of the box 50 and abut the shoulders 51, the rear end 56^a of the bar will extend above the top face of the boxing and provide a lifting lip.

The spring impelled movement of the cross latch bar downwardly is controlled, i. e., permitted and prevented, through cooperating mechanism actuated through the usual binders 29 of the shuttle boxes as moved outwardly by the entry of the shuttle therein and as moved inwardly by their springs 31 when the shuttle is driven from the box. Accordingly, a rock shaft 58 extends across the lay beam and below the opposite shuttle boxes and is journalled in bearings 59 having brackets 60 secured to the forward side face of the lay beam 5. Below each shuttle box, a crank arm 61 is affixed to the rock shaft 58 through its sleeve 62 and is positioned to cause its enlarged and flattened upper end 63 to rest against the inner end 32 of the shuttle box binder 29. A coil spring 64 encircles the shaft 58 between the shuttle boxes and has its opposite ends anchored to the lay beam 5 and to the shaft 58 so that the rock shaft normally tends to press the upper ends 63 of the crank arms 61 inwardly against the inner end 32 of the binder. Outward movement of a binder through the entry of the shuttle in the box will therefore through the crank arms 61 rock the shaft 58 forwardly, and the exit of the shuttle from the box will permit the binder springs 31 to return the binders with the coil spring 64 returning the crank arm 61 and

reversely rotating the rock shaft 58. Between the sleeve 62 of the crank arm and the outer bearing 59 beneath the shuttle box at that side of the loom mounting the dual cam 5 and pitman, the sleeved rear end 65 of a trip arm 66 (Figures 4 and 5) is affixed to the shaft and rocked thereby, the forward end of this trip arm extending between the sides of the boxing 50 and underlying the rearward 10 end or lifting lip 56^a of the latching member. When the binder 29 is moved outwardly by the entry of the shuttle in a shuttle box, therefore, the rock shaft 58 will be rotated forwardly and the trip arm 66 will be lowered 15 permitting the coil spring 56^b to move the cross bar 57 of the latch downwardly to latch the pitman bar and crank arm together for reciprocation through power operation of the cam shaft 39. The rear end of the latch bar 20 is only positioned for engagement by the trip arm 66 when the crank arm 12 is in the position alining the race plate on the frame carried by the rock shaft with the shuttle boxes 6 and their race plate extension 22 which is 25 the position occupied by these parts when the rock shaft and the frame have returned from a forward movement of their initial position, 30 this return being figured through the cam drive to occur just prior to the ejection of the shuttle from a box. If the shuttle actuating mechanism should for some reason fail and 35 the shuttle not enter the box, the pitman bar will continue to reciprocate without moving the crank arm since the lower end of the latch bar 57 will remain raised by the trip arm 66 to clear the upper edge of the boxing 50. Likewise as above stated, the trip arm 66 is 40 only lowered to latch the crank arm 12 and pitman bar when the shuttle has entered the shuttle box.

The pairs of cams 40 and 41 mounted upon 45 the power shaft 39 are rotated by the shaft in timed relation both to the shed reversing mechanism and to the shuttle operating mechanism and the cams will be figured and timed through the shaft to effect reciprocation of the pitman bar in this timed relation 50 and between successive filling inserting movements of the shuttle. Positive control and positively effected movement of the pitman at all times is secured through the configuration 55 of these cam surfaces.

In the operation of the loom, the cam shaft 39 continuously rotates and the cams therefore must be provided with a "dwell" or inactive portion which as shown comprises 60 a half section, making the pitman inoperative during the period of filling inserting throw of the shuttle.

In Figure 4, the parts are shown in the position they occupy after the shuttle has left 65 the box, unlatching the crank arm 12 from

the pitman, and with the shuttle midway of its throw. The cam shaft rotates in a clockwise direction, and a quarter section "D" of "dwell" surface on cam 40 (half of the "throw" of the shuttle) has already moved past the abutment 44 while a corresponding "dwell" section D' of cam 41 has similarly moved past its abutment 45. Taking the movements of the cam in Figure 4 with the shuttle thrown and midway through the 70 shed: The second quarter section of "dwell" surface "A" on cam 40 moves past abutment 44 while the corresponding second section of "dwell" surface A' on cam 41 passes over its abutment 45, leaving the pitman stationary. 75 At the end of this "dwell", the shuttle enters the box at the opposite side of the loom latching the crank arm and pitman through shaft 58 so that as the next and active quarter section "B" of cam 40 at the rear side of the 80 loom operates against its abutment 44, this crank arm is moved forwardly with the pitman. This brings the cams at the end of the forward throw of section B of cam 40, to the 85 positions shown in Figure 5. During the quarter revolution movement of section B of cam 40 effecting a positive outward movement of abutment 44 with its pitman bar and connected crank shaft, the correspondingly receding section B' of cam 41 moves past the 90 abutment 45 and permits the latter to move outwardly with the pitman bar.

The parts having thus moved to the position shown in Figure 5, continued rotation of cam shaft 39 causes a return movement of 100 the pitman; i. e., as the cams now continue to rotate, the projecting quarter section C' of cam 41 engages abutment 45 and effects a positive rearward movement of the pitman bar. At the same time, the receding section 105 C of cam 40 correspondingly moves rearwardly from its abutment 44 permitting movement thereof with the pitman bar as the latter is positively moved rearwardly through cam 41. This rearward movement 110 brings the batten and race frame back to its original position with its shuttle race 20 alined with the shuttle boxes as in Figure 4, and is timed to terminate as the picker stick begins its movement to eject the shuttle, the 115 lifting finger end 56^a of the latch being positioned over the lower end of the trip arm 66 which is immediately lifted to unlatch the crank arm 12 from the pitman as the shuttle leaves the box.

As this return point is reached in the revolution of the cams, their respective "dwell" sections D, A and D', A' are positioned for engagement with the abutments 44 and 45 respectively holding the pitman bar stationary during the next half revolution of the cam shaft during which the shuttle is thrown.

The pitman is therefore given a complete reciprocation between successive filling inserting movements or throws of the shuttle.

the pitman reciprocating movements being effected during the half revolution of the cam shaft while the shuttle remains in a shuttle box. Because of the configuration and coaction of the positively acting and receding portions of these cams, the to and fro movement of the pitman, crank arm and its rock shaft and support frame, are positively controlled at all times. The automatic latching control effected through the physical cooperation of the shuttle with the shuttle boxes prevents movement of the batten and race frame until the shuttle has entered a box and prevents "break outs" of the shuttle by positively retaining the intermediate race plate section 20 in alined relation to the shuttle boxes while the shuttle is passing from box to box by releasing the frame for reciprocation only after the shuttle has entered a box.

The batten mechanism described is one that may be readily detached from the loom for repair or replacement; it has the double function of beating up the filling and combing the warp shed resulting in a finer product free from the imperfections caused by "mats"; the automatic shuttle control of its actuating mechanism obviates the possibility of "break outs"; and the positive control of its actuating mechanisms ensures accuracy in timing.

The provision of a straight cross beam similar to a lay beam but fixed on the frame with its top face cut down between its opposite ends to a plane permitting a swinging race plate to overlie its top face and aline with the bases or floors of shuttle boxes mounted on the tops of its opposite ends, is not only advantageous in that the alinement of the boxes is ensured and maintained since they are carried at opposite ends of a straight beam, but in that it serves as a mount for a loom-traversing rock shaft cooperating with its opposed shuttle boxes and controlling batten and race plate reciprocating mechanism mounted at one side of the loom, and serves also as a mount for race plate positioning stops.

While the described mechanisms represent preferable structural embodiments of the inventive thought involved, they are intended as illustrative rather than restrictive of the invention. The right is reserved, accordingly, to make structural changes adapting the invention to conditions of manufacture and varying types of looms in consonance with the spirit of the invention and the scope of the appended claims.

What I claim, therefore, and desire to secure by Letters Patent is:

1. In a loom, a frame, stationary shuttle boxes mounted at opposite sides thereof in alinement, shed forming means, filling inserting means including a shuttle and operating mechanism therefor, a race plate extend-

ing between said shuttle boxes, a support therefor movable from a filling inserting position alining said plate with said shuttle boxes toward the fell of the cloth and back again to alined position, a batten carried by and moving with said support and race plate toward and from the fell in timed relation to and between successive filling inserting movements of the shuttle, and mechanism for reciprocating said support including a continuously reciprocating actuator, and means for connecting said support and actuator operated by and during the period of occupancy of a shuttle box by the shuttle to couple said actuator to said support for joint reciprocation thereof during said period.

2. In a loom, a frame, stationary shuttle boxes mounted at opposite sides thereof in alinement, shed forming means, filling inserting means including a shuttle and operating mechanism therefor, a race plate extending between said shuttle boxes, a support therefor movable from a filling inserting position alining said plate with said shuttle boxes toward the fell of the cloth and back again to alined position, a batten carried by and moving with said support and race plate, an actuator continuously reciprocating in timed relation to the shuttle operating mechanism, an arm connected to said support, and means for detachably latching said actuator to said arm automatically operated to latch the arm and actuator by the entry of the shuttle in a shuttle box and operated to release said arm from the actuator by the discharge of the shuttle from said box for a filling inserting operation.

3. In a loom, shed forming means, filling inserting means including shuttle boxes, a shuttle, and operating mechanism therefor, a batten, a supporting frame therefor mounted for movement therewith toward and from the fell of the cloth, actuating mechanism operating in timed relation to the shuttle operating mechanism for reciprocating said frame toward and from the fell, and means for preventing operation of said mechanism to move the frame prior to the entry of the shuttle in a shuttle box.

4. In a loom, shed forming means, filling inserting means including stationary alined shuttle boxes, a shuttle, and operating mechanism therefor, a race plate and batten, a common support therefor mounted for reciprocating movement therewith toward and from the fell of the cloth and relatively to said boxes from a filling inserting position with the race plate alining with said shuttle boxes, actuating mechanism operating in timed relation to the shuttle operating mechanism for reciprocating said support toward and from the fell, including shuttle controlled means for preventing operation of said actuating mechanism to so move said

support prior to the entry of the shuttle in a shuttle box.

5. In a loom, a frame, a stationary straight cross beam mounted thereon carrying alined shuttle boxes at opposite sides of the frame and having its top face between said boxes in a plane depressed below that of the bases of said boxes, shed forming means, filling inserting means including a shuttle and operating mechanism therefor, a race plate extending between said shuttle boxes, a support therefor movable from a filling inserting position with the race plate overlying the depressed face of said beam and alined with said shuttle boxes toward the fell of the cloth and back again to alined position, a batten carried by and moving with said support and race plate, actuating mechanism operating in timed relation to the shuttle operating mechanism for reciprocating said support toward and from the fell, including shuttle controlled means carried by said beam and associated with the shuttle boxes thereon for preventing operation of the actuating mechanism to reciprocate said support prior to the entry of the shuttle in a shuttle box.

6. In a loom, a frame, stationary shuttle boxes mounted thereon in alinement at opposite sides thereof, shed forming means, filling inserting means including a shuttle and operating mechanism therefor, a race plate extending between said shuttle boxes, a support therefor movable from a filling inserting position alining said plate with said shuttle boxes toward the fell of the cloth and back again to alined position, a batten carried by and moving with said support and race plate, a rock shaft upon which said support is mounted for reciprocation, a shaft rotating in timed relation to said shuttle operating mechanism, dual complemental cams mounted thereon, a pitman bar having spaced cam engaging abutments harnessed to said shaft and cams and reciprocated by the latter in timed relation to the shuttle operating mechanism, a crank arm on said rock shaft, and means latching said pitman bar and crank arm together for reciprocation, said means being controlled and actuated through the entry of the shuttle in a shuttle box.

7. In a loom, a batten supporting frame, a rock shaft on which said frame is mounted for reciprocation, a crank arm on said rock shaft, and power driven means for reciprocating said crank arm comprising a power driven shaft, dual complemental cams mounted thereon in axially spaced relation, a pitman bar guided for reciprocation to ride over said shaft and having spaced abutments alined with and engaged by said cams to effect reciprocation thereby of the pitman bar, a latch movable to connect said bar and crank arm for reciprocation and to discon-

nect said bar and arm, and shuttle controlled means for actuating said latch.

8. In a loom, stationary shuttle boxes mounted at opposite sides thereof in alinement, shed forming means, filling inserting means associated with said shuttle boxes, a batten mounted between said shuttle boxes for movement relatively thereto toward and from the fell of the cloth, and mechanism operated in timed relation to and between filling insertions for moving said batten toward and from the fell, said mechanism including a continuously reciprocating element and means operated by the entry of a shuttle in a shuttle box detachably to connect said element and batten for joint reciprocation.

9. In a loom, stationary shuttle boxes mounted at opposite sides thereof in alinement, shed forming means, filling inserting means, a batten and race plate mounted for movement in unison relatively to said shuttle boxes from a filling insertion position with said race plate alined with the shuttle boxes toward and from the fell of the cloth, and mechanism for reciprocating batten and race plate from said filling inserting position alined with said shuttle boxes toward and from the fell of the cloth including a continuously reciprocating element, a connector between said element and said race plate and batten operative detachably to connect and cause joint reciprocation thereof, and means traversing the loom and cooperating with the shuttle boxes at opposite sides thereof operative to position said connector for reciprocation of the batten and race plate responsive to the entry of a shuttle in a shuttle box.

10. In a loom, a stationary straight cross beam having shuttle boxes mounted on opposite ends thereof and alined thereby, shed forming means, filling inserting means associated with said shuttle boxes, including a shuttle and operating mechanism therefor, a batten and race plate, a common support therefor mounted for reciprocating movement therewith toward and from the fell of the cloth from a position with the race plate overlying said beam and alined with the floors of the shuttle boxes for filling insertion, and mechanism for so reciprocating said support between successive filling insertions conditioned for operation by the entry of a shuttle in a shuttle box and including means traversing the loom and cooperating with the shuttle boxes at opposite ends of said beam.

11. In a loom, stationary shuttle boxes mounted at opposite sides of the loom in alinement, shed forming means, filling inserting means associated with said shuttle boxes including a shuttle and operating mechanism therefor, a batten and race plate, a common support therefor mounted for reciprocating movement toward and from the fell of the cloth relatively to said shuttle boxes from a position with the race plate alined with the

shuttle boxes for filling insertion, mechanism at one side of the loom for so reciprocating said support, and means for conditioning said mechanism for operation between successive filling insertions including means traversing the loom cooperating with the shuttle boxes at opposite sides thereof and actuated by the entry of a shuttle in a shuttle box.

12. In a loom, a frame, a stationary straight cross beam mounted thereon, shuttle boxes fixed thereon at opposite sides of the loom and alined thereby, with the top face of said cross beam between the shuttle boxes depressed to a plane below the floors of said boxes, shed forming means, filling inserting means associated with said shuttle boxes including a shuttle and operating mechanism therefor, a batten and race plate, a common support therefor mounted for reciprocating movement therewith toward and from the fell of the cloth from a filling inserting position with the race plate overlying the depressed face of said cross beam and alined with the floors of said boxes, and mechanism for so reciprocating said support in timed relation to and between successive filling insertions including support reciprocating mechanism at one side of the loom including means for connecting said support and mechanism for joint operation having a controlling element mounted on said beam and traversing the loom, cooperating with the shuttle boxes at opposite sides thereof and actuated by the entry and detention of a shuttle in a shuttle box operatively to connect said support and mechanism for joint operation.

13. In a loom, stationary shuttle boxes mounted at opposite sides thereof in alinement, shed forming means, filling inserting means associated with the shuttle boxes including a shuttle and operating mechanism therefor, a race plate extending between said shuttle boxes, a support for the race plate movable therewith relatively to said boxes from a filling inserting position alining said plate with said boxes toward the fell of the cloth and back again to alined position, a batten carried by and moving with said support, and mechanism for reciprocating said support toward and from the fell including a continuously reciprocating element and means automatically operative to connect said element and support for joint reciprocation upon the entry of a shuttle in a shuttle box and during its period of occupancy thereof and automatically operative to disconnect said parts by the discharge of the shuttle from a box.

BENJAMIN D. HAHN.
